UNITED STATES PATENT OFFICE.

OLIVER D. H. BENTLEY, OF ROSLINDALE, MASSACHUSETTS, ASSIGNOR TO B. F. STURTEVANT COMPANY, OF HYDE PARK, MASSACHUSETTS, A CORPORATION OF MASSACHUSETTS.

STEAM TURBINE.

Application filed March 5, 1919. Serial No. 280,807.

To all whom it may concern:

Be it known that I, OLIVER D. H. BENTLEY, a citizen of the United States, residing at Roslindale, in the county of Suffolk 5 and State of Massachusetts, have invented certain new and useful Improvements in Steam Turbines; and I do hereby declare the following to be a full, clear, and exact description of the invention, such as will enable others skilled in the art to which it appertains to make and use the same.

The present invention relates to elastic fluid turbines and more particularly to an elastic fluid turbine having rotors which 15 turn in opposite directions.

With elastic fluid turbines in order to secure a commercial degree of efficiency it is necessary that those portions which handle the high velocity steam, such for example 20 as the expanding nozzles and the steam receiving buckets, move with relation to one another at high velocity. Heretofore, it has been the common practice for one set 25 of the steam handling devices, usually the nozzles and redirecting vanes or buckets, to remain stationary and the buckets alone to move. The relative velocity of nozzle and bucket was, therefore, the same as the linear velocity of the bucket which, for 30 practical reasons, was limited.

The principal object of the present invention is to increase or improve the efficiency of elastic fluid turbines by increasing the relative velocities of the steam 35 handling devices without increasing the absolute or linear velocities thereof. To the accomplishment of this object I have provided a pair of rotors arranged to turn 40 in opposite directions and each provided with cooperating steam handling devices, thus permitting double the relative speeds without any increase in the absolute speed 45 of the steam handling devices.

Another object of the present invention 50 is to provide durable and efficient means whereby the oppositely directed rotations of the turbine rotors shall impart rotational movement in the same direction to a single power or driving shaft and preferably at 55 a lower speed.

Still another object of the present invention is to provide a compact, unitary structure, comprising a counter rotating turbine and transmission mechanism having a single 60 low speed power or driving shaft.

Still another object is to provide a complete and efficient lubricating system for the transmission mechanism of a counter rotating turbine.

To the accomplishment of these objects 60 the present invention comprises the devices and combinations of devices as hereinafter described and more particularly defined in the claims. Other features of the present invention are set forth in the following 65 specification, as will be apparent to those skilled in this art.

In the accompanying drawings which illustrate what is now considered to be a preferred embodiment of the present invention, Figure 1 is a view in side elevation of the complete turbine and transmission; Fig. 2 is an end elevation thereof looking from the right in Fig. 1; Fig. 3 is a top plan view on the line 3-3 of Fig. 1 showing on an enlarged scale the rotating portions of the turbine and of the gearing partly in section and partly in plan; Fig. 4 is a fragmentary view on a still larger scale showing the two rotors of the turbine 80 in transverse section on the line 4-4 of Fig. 3; Fig. 5 is a fragmentary view showing the rotors in longitudinal section, the section extending through the hubs of the rotors; Fig. 6 is a detail cross-sectional view 85 on the line 6-6 of Fig. 3; Fig. 7 is a detail perspective view of one of the flexible keys shown in Fig. 3; Figs. 8, 9 and 10 are conventional views showing the relation of the gears in the planes indicated by the 90 lines 8, 9 and 10, respectively, in Fig. 3; Fig. 11 is a detail perspective view of one of the bucket blades; and Fig. 12 is a diagrammatic plan view of the oiling system.

In the turbine illustrated in the drawings, the turbine and transmission gearing are shown in a unitary structure enclosed in a single casing. The turbine proper comprises two rotors which turn in opposite 100 directions, and upon one of which the nozzles are located. One of the rotors is mounted upon a cylindrical sleeve or hollow shaft surrounding the shaft of the other rotor. Both rotor shafts are 105 connected to a pair of oppositely disposed secondary shafts by independent trains of speed reduction gearing with an idler in one train to reverse the direction of rotation. The secondary shafts in turn trans- 110

mit power by speed reduction gearing to a single or common power or driving shaft which is in axial alignment with the two rotor shafts.

5 The casing within which all the mechanism of the turbine is enclosed comprises an integrally formed lower member or body 6 having a base 7, and an upper member or cover 8, the two casing members being 10 divided in the horizontal axial plane of the rotors and being secured together by bolts 9 passing through the bolting flanges 10. The casing is divided transversely by a wall 11 into two chambers 12 and 13, the 15 former containing the rotors, and the latter containing the gearing connecting the rotor shafts with the driving shaft.

The turbine proper, or power producing element, comprises two oppositely turning 20 rotors located within the chamber 12. For convenience of description these will be referred to—one as the primary rotor and the other as the secondary rotor. The primary rotor carries the steam nozzles 25 and one set of buckets or vanes, while the secondary rotor is provided with two sets of buckets, all the nozzles and buckets being in substantially the same plane of rotation. The steam from the rotating nozzles 30 is directed into the oppositely rotating buckets of the secondary rotor, from which it passes into the buckets of the primary rotor, thence back into the second set of 35 secondary rotor buckets, from which it finally escapes into the casing.

The primary rotor comprises a hollow disk or wheel 14 carried at the inner end of the hollow shaft 15 journaled in the bearing 16 at one end of the casing. This disk is preferably made in two sections 17 and 18, as shown clearly in Fig. 5, section 17 being integral with the hollow shaft 15, while section 18 is secured to the section 17 by rivets 19 and is integral with a solid shaft 20, co- 45 axial with the hollow shaft 15, and extending in the opposite direction therefrom.

The secondary rotor comprises a bucket wheel 21 adjacent the primary rotor 14 and is integrally formed with the hollow shaft 22 50 mounted to rotate upon the shaft 20 of the primary rotor, a bearing sleeve 23 of anti-friction metal being secured within the hollow shaft 22 to provide a bearing surface for shaft 20.

55 Steam is supplied to the chamber 24 in the interior of the primary rotor through the hollow shaft 15 having inlet ports 25 communicating with an annular steam chamber 26 which surrounds the shaft and receives 60 steam through an inlet passage 27 which is fed by a pipe leading from the boiler. Centrally located in the bearing 16 is a perforated ring 28, surrounding the shaft 15 and interposed between the inlet ports 25 and the 65 annular steam chamber 26, which serves to

prevent the entrance of foreign matter into the turbine. This perforated ring is commonly known as a cage or lantern. Suitable packing 29 is provided, surrounding the shaft 15, within the casing 16, at each side 70 of the lantern 28 to prevent leakage of steam from the supply, either to the exterior or interior of the casing. As shown in Fig. 6, the inlet ports 25 are formed with their rear portions undercut so as to facilitate the entrance 75 of the steam as the shaft rotates at high speed in the direction of the arrow.

The hollow interior of the primary rotor serves as a rotary steam chest from which steam is supplied to a plurality of expanding nozzles 30 outwardly spaced an equal distance from the axis of the rotor and equidistant from each other. The preferred form and construction of these nozzles is shown in Figs. 4 and 5. The expanding passages 80 are formed between overlapping blades 31 which space apart the two sections 17 and 18 of the primary rotor and which are held therebetween against centrifugal displacement by dovetail joints 32. Rivets 33 pass 85 through the blades 31 holding them securely in position and binding together the two sections of the rotor. The nozzles deliver expanded steam from the chamber 24 within the primary rotor to buckets 34 formed in 90 the secondary rotor, thus causing rotation in opposite directions of the two rotors. These buckets are concentrically arranged about the axis of the rotors, equi-distant from each other, and in the radial plane of rotation of 95 the nozzles. Preferably, in order further to extract energy from the steam, the primary rotor is also provided with a plurality of peripheral buckets 35 arranged to receive the steam from the buckets 34 of the secondary 100 rotor, and the secondary rotor is further provided with a plurality of peripheral buckets 36 arranged to receive the steam after it has passed through the buckets 35 of the primary rotor. These buckets, together with the nozzles 30, are all concentrically arranged about the axis of the rotors and are all in the same plane of rotation, so that the steam in passing through the nozzles and buckets produces no end thrust of the rotors. 105

110 Preferably the nozzles are so shaped as to expand the steam to substantially the pressure of the exhaust steam in the casing so that any steam which escapes laterally from between adjacent rows or rings of nozzles or buckets cannot produce end thrust on the rotors tending to separate them axially.

115 As the steam flows from the nozzles into the successive rings of buckets, rotation in opposite directions is imparted to the rotors. 120 The buckets, in each row, successively reached by the steam, are increased in axial width as the velocity of the steam becomes decreased, so as to present a greater passage area to the slower moving steam. Obvi- 125 130

ously the velocity of the steam may be still further utilized, if desired, by employing additional concentric rows of buckets on each rotor.

5 The buckets of the rotors are constructed by arranging bucket blocks 38 in rows concentric with the axis of the rotors between the rotor shells, which forms one side of the buckets, and rings 39 which forms the opposite side thereof. The blocks themselves form the concave bottom of the buckets and are preferably formed with integral studs 40, as shown in Fig. 11, which project through the rotor shells and through the 15 rings 39 and are headed over, thus holding the blocks 38 and the rings 39 in place.

The steam exhausts from the outer row of buckets into the turbine chamber 12 and thence through an exhaust conduit 42 to the 20 atmosphere. To prevent the escape of steam along the hollow rotor shaft 22 into the chamber 13, packing rings 43 are provided, while a suitable form of labyrinth packing, such as the concentric grooves 44, is employed to prevent similar escape of steam 25 between the primary rotor shaft 20, and the bearing sleeve of the secondary rotor shaft 22.

In order to impart motion from the oppositely turning rotor shafts to a single power 30 or driving shaft and at a greatly reduced speed transmission mechanism is provided. This comprises a pair of counter shafts 48 journaled in bearings 49, carried by the casing within the chamber 13. The hollow 35 secondary rotor shaft 22 is geared directly to these counter shafts 48 through a pinion 50 fixed to said rotor shaft and gears 51 fixed on the counter shafts 48. The solid primary rotor shaft 20 is also geared to 40 these counter shafts through a pinion 52 fixed on the said rotor shaft and meshing with the intermediate or idler pinions 53 rotatably mounted within the casing which drive the gears 54 on the counter shafts. 45 The two oppositely rotating members of the turbine are thus held to rotate in fixed relation, one to the other.

The counter shafts 48 are connected to a single common driving or power shaft 55 by means of pinions 56, keyed to the counter shafts by one or more flexible keys 57, and a gear 58 fixed to the driving shaft 55. This driving shaft 55 is coaxial with the rotor shafts and surrounds at its inner end the free end of the primary rotor shaft 20, a bearing sleeve 59 of antifriction metal being secured within the hollow end of shaft 55 to provide a bearing surface for rotor shaft 20. Suitable bearings 60 within the casing 60 support the driving shaft 55.

The rotors of the turbine which are rotating in opposite directions, each at high speed, say, for example, at the rate of 4000 revolutions per minute are thus geared down so that the final driving shaft will rotate

at a greatly reduced speed, making approximately 500 revolutions per minute.

The flexible keys 57 are somewhat bowed leaf-spring members illustrated in perspective by Fig. 7. They are used in order to 70 compensate for any slight inaccuracies of the machine, thus ensuring transmission of power equally through both counter shafts and gearing and avoiding excessive bearing pressure. 75

Two counter shafts have been shown in the drawings, located diametrically opposite one another in order to balance the thrust of the gears on the rotor shafts. Any number of counter shafts with gear sets can be 80 used, and preferably the design of the turbine will be such that as power is increased, as by the use of steam at higher pressure, additional pairs of counter shafts with gear sets can be added to transmit the additional 85 power.

The lubrication of the transmission mechanism is accomplished by means of a pair of pumps 61 which draw the oil from the lower portion of the transmission base, and produce a constant circulation of oil under pressure throughout the mechanism of the turbine. Any ordinary or suitable form of rotary or gear pumps may be used and they may be actuated as shown in the drawing, by 90 connection with the ends of the counter shafts. The circulation of the oil is diagrammatically illustrated by Fig. 12, in which the general outline, in plan, of the shafts and gearing, is shown by dot and dash lines and the oil passages and lubricated portions of the bearings by heavy solid lines. As both counter shafts are lubricated in the same manner, the circulation of the oil in one shaft only is shown in the diagram. 100 105

The counter shafts are provided with central oil passages A and lateral branch passages B, through which the oil is forced from the pumps 61, to the bearings of the shaft. From the right hand bearings of the counter shaft the oil is conveyed through conduits C to the right hand bearing of the driven shaft and thence through lateral passages D in the driven shaft to a central passage E therein, and along the latter to the bearing surface between the primary rotor shaft 20 and the bearing sleeve 59 on the driven or power shaft 55. A portion of the oil from passage E is forced through a central passage F in the primary rotor shaft, and lateral branches G to the bearing sleeve 23 between the primary and secondary rotor shafts. A conduit H, similar to the conduit C, conveys oil from the middle counter shaft bearings to the left hand bearing 60 of the driven shaft. From this conduit H, oil also flows into central passages I within the idlers 53 and thence through lateral passages J to the bearings of the idlers. The oil is pre- 110 115 120 125 130

vented from escaping from the bearing between the primary rotor shaft 20 and the bearing sleeve in the secondary rotor shaft 22 and into the space between the two rotors 5 and into the turbine chamber, by two sets of circular oil intercepting grooves K, shown also in Fig. 5, which convey the oil through passages L to the faces of the gears 50, 51, through holes drilled between the teeth of 10 gear 50.

Two sets of circular grooves M similar to the grooves K are located between the latter and the rotor end of the secondary rotor shaft and serve to trap any exhaust steam 15 which tends to work into the bearing between the primary and secondary rotor shafts, from the turbine chamber. The course of the steam after being intercepted by the grooves M is indicated by arrows in 20 Fig. 5 through conduits N in the secondary rotor shaft and passages O in the casing to an annular chamber P and thence through a suitable passage in the casing to the open air.

25 The operation of the turbine illustrated in the drawings is as follows:

Steam from any suitable source of supply is admitted through inlet pipe 27 into the steam chamber 26, whence it passes into the 30 hollow interior of the primary rotor shaft. It then flows through the nozzles 30 which deliver the steam fully expanded and at high velocity into the inner ring of buckets or vanes of the secondary rotor, from which it 35 flows into the vanes or buckets of the primary motor, and thence into the outer ring of buckets of the secondary rotor, each set of buckets extracting successively a portion of the energy of the steam which is correspondingly reduced in velocity until it 40 finally is discharged into the exhaust space of the casing and escapes through the exhaust pipe 42.

The high speed rotations in opposite directions of the two rotor shafts 20 and 22 produced by the flow of steam through the nozzles and buckets are transmitted to counter shafts 48 by the separate trains of speed reducing gearing, the idler gears 53 reversing 45 the direction of rotation of the primary rotor shaft 20 so that both rotors drive the counter shafts in the same direction. The counter shafts in turn drive the power shaft through the pinion 56 which, by reason of 50 their flexible keys 57, adjust themselves by slight rotational movement on their respective shafts to compensate for inaccuracies in machine work, thus equalizing the torque upon each counter shaft and its gearing.

60 The power shaft is thus driven at a comparatively low rotational speed, suitable for general commercial requirements, while the rotors operate at the proper high relative speed to give the maximum efficiency.

65 While the construction and arrangement

herein shown and described is in accordance with what is now considered to be a preferred form of the invention, it will be understood that the same may be varied or modified in different particulars without departing from the spirit and scope thereof. 70

Having now described the invention, what I claim is:

1. An elastic fluid turbine having, in combination, a casing, a rotor mounted in the casing, comprising a rotary steam chest, having a hollow hub and a plurality of steam delivery nozzles in communication with the chest, a steam chamber surrounding the hub for supplying steam to the steam chest, the hub being provided with ports to permit the passage of steam from the chamber to the chest, the rear walls of the ports as determined by direction of rotation being undercut. 75

2. An elastic fluid turbine having, in combination, a casing, a rotor mounted in the casing, comprising a rotary steam chest, having a hollow hub and a plurality of steam delivery nozzles in communication with the 80 chest, a steam chamber surrounding the hub for supplying steam to the steam chest, the hub being provided with ports to permit the passage of steam from the chamber to the chest, packing surrounding the hub at each 85 side of the ports and a cage surrounding the ports and located between the chamber and the hub, the outer side walls of the cage flaring outwardly and engaging the packing. 90

3. An elastic fluid turbine having, in combination, a casing, a pair of rotors mounted within the casing, one of the rotors being provided with steam delivery nozzles and the other with buckets, the first mentioned rotor comprising a hollow shaft provided 100 with a radial flange to form one side of the rotor, a solid shaft in axial alignment with the hollow shaft provided with a radial flange to form the other side of the rotor, the flanges being spaced apart in rigid relation, and blocks having tongue and groove connection with said flanges and fixedly secured therebetween to form the steam delivery nozzles, and means for supplying steam to the hollow shaft, and means for 105 exhausting steam from the casing. 110

4. An elastic fluid turbine having, in combination, a casing, a pair of rotors mounted within the casing, one of the rotors being provided with nozzles and the other with buckets, the first mentioned rotor comprising a hollow wheel having opposite sides formed integrally with rotatably supported shaft sections extending on each side of the wheel, the last mentioned rotor comprising a wheel mounted on the end of a hollow shaft surrounding one of said shaft sections, and means for supplying steam to the nozzles, and means for exhausting steam from the 120 casing. 125

5. An elastic fluid turbine having, in combination, a casing, a pair of rotors coaxially mounted within the casing and provided with steam handling devices adapted to turn the rotors in opposite directions, shafts upon which the rotors are mounted, a single power shaft in alignment with the rotor shafts, and connections between the two rotor shafts and the power shaft for imparting rotation at reduced speed to the power shaft. 10
6. An elastic fluid turbine having, in combination, a casing, two rotors mounted within the casing and provided with steam handling devices, shafts for the rotors, a single power shaft, connections between the power shaft and one of the rotor shafts comprising a countershaft and a gear secured by a flexible key to the countershaft, and gearing between said power shaft and the other rotor shaft arranged to reverse the direction of rotation imparted from said other rotor shaft. 20
7. An elastic fluid turbine having, in combination, a pair of rotors mounted within the casing arranged to rotate in opposite directions, shafts for the rotors, a power shaft mounted in the casing in axial alignment with the rotor shafts, gearing between the rotor shafts and the power shaft to impart rotations to the power shaft in the same direction from the oppositely rotating rotor shafts, and means for supplying steam to and exhausting it from the rotors. 30
8. An elastic fluid turbine having, in combination, a casing, a pair of oppositely turning rotors mounted within the casing, means for conducting steam to and away from the rotors, shafts for the rotors, a power shaft in axial alignment with the rotor shafts, a plurality of counter-shafts symmetrically disposed around the rotors, shafts and power shaft, and gearing between the rotor shafts and the counter-shaft and between the counter-shaft and the power shaft. 40
9. An elastic fluid turbine having, in combination, a casing, two rotors mounted within the casing and provided with steam handling devices, a shaft for one of said rotors, a hollow shaft for the other rotor mounted upon the first mentioned shaft, a power shaft in axial alignment with said rotor shafts and having bearing engagement with one of the said shafts, a plurality of counter-shafts symmetrically arranged about said rotor shafts and power shaft, and gear connections between the rotor shafts and the counter-shaft and between the counter-shaft and the power shaft. 50
10. An elastic fluid turbine having, in combination, a casing, a pair of rotors
- mounted within the casing and adapted to turn in opposite directions, shafts for the rotors, one of said shafts being hollow and mounted upon the other shaft which projects beyond the end of the hollow shaft, a power shaft in axial alignment with the rotor shafts, co-operating external and internal bearing surfaces between the end of the power shaft and the projecting end of the rotor shaft, a counter-shaft, a gear connection between the counter-shaft and the hollow rotor shaft, a gear connection between the counter-shaft and the other rotor shaft, one of the connections comprising an idler gear to reverse the direction of rotation, and gearing between the counter shaft and the power shaft. 65 70 75
11. An elastic fluid turbine having, in combination, a casing, a pair of rotors mounted within the casing and arranged to rotate in opposite directions, means for supplying steam to and conducting it away from the rotors, shafts for the rotors, a power shaft, and two independent connections between the rotor shafts and the power shaft, one of said connections being yielding and tending to equalize the power transmitted through the two connections. 80 85
12. An elastic fluid turbine having, in combination, a casing, a pair of rotors mounted within the casing, and arranged to rotate in opposite directions, means for supplying steam to and conducting it away from the rotors, shafts for the rotors, a power shaft, and a plurality of yielding independent connections between the rotor shaft and the power shaft tending to equalize the power transmitted through said connections. 90 95
13. An elastic fluid turbine having, in combination, an integral casing provided with a transverse partition to form an exhaust chamber for the turbine and a chamber for gearing, a rotor mounted within the exhaust chamber, a gearing mounted within the transmission chamber, and a cover for the casing comprising a plurality of separable parts, one part forming a closure for the top of the exhaust casing of the turbine. 100 105
14. An elastic fluid turbine having, in combination, an integral casing provided with a transverse partition to form an exhaust chamber for the turbine and a chamber for the gearing, a rotor mounted within the exhaust chamber, gearing mounted within the transmission chamber, and independently removable covers for the exhaust chamber and for the transmission chamber. 110 115

OLIVER D. H. BENTLEY.
